SOCKET ADAPTER

Frank C. De Reamer and Arthur W. Clauder,
Bridgeport, Conn., assignors to General Electric
Company, a corporation of New York

Application February 25, 1939, Serial No. 258,454

14 Claims. (Cl. 173—344)

This invention relates to socket adapters, and more particularly to a socket adapter for use with a projector or reflector type of incandescent lamp.

- 5 It is an object of the invention to provide an adapter for an incandescent lamp which permits the lamp to be turned horizontally and, at the same time, to be adjusted vertically through a wide range of angles.
- 10 It is a further object of the invention to provide an adapter of the type described which comprises relatively few parts, which is light in weight and of small dimensions and which may be manufactured at low cost.
- 15 In the accompanying drawing, Fig. 1 is a view showing the adapter mounting a lamp; Fig. 2 is a cross-sectional view through the device; Fig. 3 is a sectional view along the line 3—3 of Fig. 2; Fig. 4 is a view of the interior of the 20 lamp receiving socket; Fig. 5 is a view showing the possible adjustment of the adapter from a vertical position; and Fig. 6 is a view showing the horizontal adjustment of the adapter.

Referring to the drawing, the adapter comprises generally an electric plug 10 adapted to be inserted in a plug receptacle and a receptacle 11 adapted to receive the base of an electrical device, for example, an electric lamp. In Fig. 1, the adapter is shown supporting a projector lamp 12. Such lamps are frequently used in show case window lighting and must be adjusted through a wide range of angles to project a beam of light to any point in the show case. This means that the lamp must be adjustable, both vertically and horizontally. To this end the receptacle 11 is so mounted on the plug base 10 that it may be tilted relative to the base 10 through a vertical angle of approximately 70°, as shown by Fig. 5, and also through a horizontal angle of approximately 340°, as shown by Fig. 6. By this construction it is possible to provide a wide range of adjustment for a projection lamp simply by removing the lamp from its supporting shell, threading the plug base 10 into the shell and then mounting the lamp on the adjustable receptacle 11.

Turning now to the structure of the adapter, as shown in Figs. 2, 3 and 4, it will be seen that the plug 10 is formed with a base 13 having an integral extension 14. The plug base is made of insulating material, for example, porcelain. Formed in the top of the base 13 is a recess 15 the bottom of which merges with a channel 16 formed in the extension 14. A supporting shell 17, which is formed from a portion of a sphere,

is mounted within the recess 15 with a part of the shell wall resting on the beveled edge 18 of the recess. An opening 19 is formed in the shell at the point where it rests on the beveled edge 18 of the recess to provide a flange 20 which closely grips the wall of the recess and prevents lateral displacement of the shell relative to the base 10. When assembled in the manner indicated, the shell is free to rotate in a horizontal plane relative to the plug 10. Rotation for 1 more than a complete revolution is prevented by engagement of a depending tang 21 formed on the shell 17 with an abutment 22 upstanding from the wall of the recess.

The receptacle 11 includes a supporting element 23 for a lamp socket provided with a center contact 24 and a threaded shell 25 forming another contact. The support 23 is made of any suitable insulating material, for example, a phenolic condensation product, and its outer surface is of spherical configuration in order that it may be seated within the spherical shell 17 where it closely engages the inner surface of the shell for rotative movement therein. Each side of the spherical support 23 is provided with a 25 trunnion 26 seated in bearings 27 cut in opposite sides of the edge 28 of the shell 17. There is a clearance of approximately $\frac{1}{32}$ " between the trunnions and bearings so that the supporting element is frictionally seated within the shell 30 and is merely guided in the bearings which prevent rotation in a horizontal plane relative to the shell. It should be noted that the edge 28 of the shell is formed at an angle of approximately 45° with the plug base 13. This means 35 that the supporting element 23 may rotate within the shell through an angle of approximately 70° without abutting against the edge of the shell. The range of movement is shown most clearly by Fig. 5. The trunnion and bearing 40 structure are in alignment with the central axis of the electric plug 10 so that when the support 23 is moved to the upright position shown by dotted lines in Fig. 5, the lamp base receiving shell 25 is in axial alignment with the electric 45 plug 10.

The center contact 24 and the screw shell contact 25 are located within a recess 29 formed in one end of the supporting member 23. Contact 24 is secured to the bottom of the recess 50 by a bolt 30 and the contact shell 25 is provided with ears 31 which cooperate with the bolts 32 in securing the shell to the supporting member. A sleeve 33 of insulating material, for example, porcelain is threaded down upon the outside of 55

the threaded shell 25 and has a portion 34 extending into the recess 29 to provide a supporting means for a lamp shade which is held between the sleeve and the shell. As shown more particularly in Fig. 2, the center contact 24 takes the form of a U-shaped spring member the arms of which are compressed upon engagement with the center contact of a lamp base threaded into the socket shell 25.

10 The center contact 24 is normally biased into engagement with a conducting member or arm 35 pivotally supported on a pin 36 the latter resting in a slot 37 formed in the base of the recess. Upon tilting movement of the supporting member 23 the arm 35 moves in a groove 38, formed in the supporting member, and the arm pivots about the pin 36; angular movement of the supporting member is limited by engagement of the edge of the groove with the arm 35. The pin 36 and trunnions 26 are in substantially axial alignment so that when the supporting member 23 is moved to various angular positions it will pivot about an axis in line with both the trunnions 26 and the pin 36. This means that the conducting arm 35 maintains a fixed position at all times, this position being shown by Fig. 2. The conducting arm is provided at one end with a substantially circular bearing surface 35' which maintains contact with the center contact 24 at all times irrespective of the positions to which the supporting member and center contact are moved. At the other end, the arm is formed with a flange 39 engaging a bushing 40 which, in turn, is threaded down upon one end of a coil spring 41. The other end of the coil spring is connected to a nut 42 threaded on an adjustable bolt 43. The bushing 40, spring 41, and nut 42 are disposed within the channel 16 and surrounded by the extension 14.

40 Mounted on the lower end of the plug extension 14 is a threaded shell 44 forming one contact element of the plug 10. The adjustable bolt 43 forms the other or center contact of the plug and for this purpose is provided with a head 45. The bolt 43 and the contact shell 44 are separated from one another by a disk 46 of insulating material for example, porcelain. The disk is of substantially circular configuration and bears against an inturned flange 47 of the shell 44 to hold it in position on the extension 14. The disk is provided with an opening 48 to receive the bolt 43. As shown more particularly by Figs. 2 and 3 the channel 16 is rectangular in cross-section and the disk 46 is provided with an upstanding boss 49 of corresponding rectangular form which fits in the end of the channel. This means that rotation of the disk 46 and contact shell 44 is prevented upon rotation of the adjusting bolt 43.

55 In order to connect electrically the plug shell 44 with the socket shell 25 an insulated conductor 50 is connected at one end to one of the bolts 32 holding the shell 25 in position, and at the other end is fastened to the inturned flange of the shell 44 at the point 51. The conductor passes through an opening 52 formed in the wall of the extension 14 and thence to a groove 53 in the side wall of the extension where the connection 51 is made by any suitable means, such as solder or a weld. A sufficient length of the conductor is provided to permit turning of the lamp receptacle without danger of damage or breakage of the conductor. To provide ample space in which the length of conductor may be

coiled the supporting member 23 is provided with a recess 54.

In assembling the elements of the device the lamp receptacle contacts, the conducting arm 35, the spring 41 and the nut 42 are all mounted on the supporting member 23 which is then placed within the shell 17 and the assembly mounted in the recess on the plug base 13. The shell 44 and disk 46 are then placed on the extension 14 and the adjusting bolt 43 is inserted through the opening 48 and threaded into the nut 42. Threading of the bolt 43 in the nut 42 tensions the spring 41 and draws the supporting member 23 and shell 17 down tightly upon the plug base. The pull of the spring is transmitted by the conducting arm 35 and pin 36 to the supporting member 23. However, the spring is sufficiently resilient to permit angular movement of the supporting member 23 relative to the shell 17 and to permit rotation of the shell about the plug base. The frictional force set up by the spring is sufficient to hold the supporting member and shell in whatever position they have been moved to. Adjustment of the frictional force is to be had by adjustment of the bolt 43.

In some cases it may be desirable to provide a locking means to maintain the supporting member 23 in the angular position to which it has been moved. To this end, a set screw 55 is placed in the shell 17 and the end of the screw bears against the surface of the supporting member 23 to lock it in position. This structure is advantageous in those cases where the adapter may be subject to considerable vibration such that the supporting member may be jarred out of position or where an exceptionally heavy lamp is placed in the lamp receptacle 11. However, for most ordinary purposes the supporting member 23 is frictionally held in position by the spring 41 making the use of a locking screw unnecessary or, at best, a precautionary measure.

The spring 41 not only assists in holding the elements of the adapter in assembled relationship but it also provides a conducting path for the current from the contact 45 of the plug 10 to the center contact 24 of the receptacle 11. Insertion of a lamp base in the receptacle presses the contact 24 firmly into engagement with the circular bearing surface 35' on the conducting arm so that the arm is in conducting relationship with the contact irrespective of the angular position to which the contact 24 and supporting member 23 have been moved. Upon rotation of the shell and supporting member about the base 13, the conducting arm pivots about the bushing 40 while the flange 39 makes continuous electrical contact with the bushing. A highly effective electrical contact is insured at this point by the tension of the spring 41. Rotation of the shell 17 through more than a single revolution such as would tend to twist and damage the conductor 50 is prevented by engagement of the tang 21 with the abutment 22.

While the invention has been illustrated and described with the shell 17 and the supporting member 23 having a spherical configuration, it should be manifest that the shape of these elements may be other than spherical so long as an angular adjustment between the two is provided for. The spherical configuration is advantageous, however, in that a smooth and effective frictional grip is obtained between the two members such that the lamp receptacle remains in the angular position to which it has been moved; moreover, this configuration makes possible a

compact arrangement of elements having a neat and pleasing appearance.

According to the invention it is possible to provide for a wide range of angular adjustments of a lamp simply by inserting the adapter in a lamp receptacle and mounting the lamp in the adapter. When so mounted, the lamp may be rotated through almost a complete circle and, at the same time, may be tilted angularly through an angle of approximately 70 degrees. This range of adjustment is ample for almost any use to which the lamp is to be put. When once adjusted to the selected position the adapter maintains the lamp in this position.

15 What we claim as new and desire to secure by Letters Patent of the United States is:

1. In combination, an electric plug provided with electric contacts, a member rotatably mounted on said plug, a supporting element seated upon said rotatable member and adapted for angular movement relative to said member, lamp receptacle contacts mounted on said supporting element, spring means interconnecting said supporting element and said electric plug 20 for maintaining said rotatable member and said supporting element in position on said electric plug, said spring means forming an electrical conducting path between one of said plug contacts and one of said receptacle contacts, and 25 electrical conducting means interconnecting the other of said plug and receptacle contacts.

2. An adapter of the type described comprising an electric plug base having a recess therein, electrical contacts mounted on said plug base, a spherically shaped shell rotatably mounted within said recess, a supporting member of substantially spherical configuration seated within said shell and adapted for angular movement relative to said shell, lamp receptacle contacts mounted 30 on said supporting member, an adjustable spring means interconnecting said supporting member and said plug base and adapted to hold said supporting member and said shell in assembled relationship on said base, said spring means forming an electrical conducting path between one of said plug contacts and one of said receptacle contacts, and electrical conducting means interconnecting the other of said plug and receptacle contacts.

30 3. An adapter comprising an electric plug provided with a base having a recess therein, contact members mounted on said base, a shell rotatably mounted within said recess, a supporting member seated within said shell and mounted 35 for angular movement relative to said shell and base, receptacle contact means mounted on said supporting member and including a screw threaded shell and a central contact member, a conducting arm pivotally mounted within said supporting member and having an arcuate surface bearing against said center contact member, spring means connected at one end to said arm and at the other end to one of said plug contacts to form a conducting path between said plug 40 contacts and said central contact, said spring means normally biasing said conducting arm to hold the supporting member and shell in position on said base, and means electrically interconnecting said receptacle contact and the other 45 of said plug contacts.

4. In combination, an electric plug having a recess therein, a spherically shaped shell rotatably mounted in said recess, a supporting member of substantially spherical configuration, said 50 supporting member being provided with diamet-

rically opposed bearing means for engaging the wall of said shell to support said member for annular movement within said shell, receptacle contacts mounted on said supporting member, and means electrically connecting said receptacle 5 contacts with said electric plug.

5. In combination, an electric plug having a base provided with a recess therein, abutment means formed in said recess, electrical contacts mounted on said plug base, a shell rotatably 10 mounted in the recess on said plug base, means projecting from said shell and adapted to engage said abutment means to prevent rotation of said shell beyond a predetermined position, a supporting member seated in said shell and 15 being mounted for angular movement in a plane at right angles to that of rotation of said shell, receptacle contacts mounted on said supporting member, and means for electrically interconnecting said receptacle contacts and the contacts on 20 said plug base.

6. An adapter comprising a plug base having a recess at one end and being provided with an extension at the other end, said extension being formed with a channel merging with said 25 recess, a screw threaded shell mounted on the end of said extension and forming one plug contact, a rotatable bolt insulated from said shell and disposed within said channel to form the other of said plug contacts, a shell rotatably 30 mounted in said recess, a supporting member seated within said shell and angularly movable in a plane at right angles to that of the plane of rotation of said shell, receptacle contacts mounted on said supporting member and comprising a screw shell and a centrally disposed 35 spring contact member, a conducting arm pivotally mounted within said supporting member and having a contact surface in engagement with said center receptacle contact, spring means disposed between said conducting arm and said adjustable bolt and being located in the channel in said extension, said spring means providing a conducting path from said adjustable bolt to said center contact and being adjustable on said 40 bolt for holding the supporting member and shell in position on said plug base, and an insulated conductor interconnecting said plug and receptacle shells.

7. In combination, an electric plug comprising 50 a base having a recess therein, plug contacts mounted on said base including a threaded shell and a center contact, a supporting shell rotatably mounted within said recess, a supporting member pivotally mounted within said supporting shell and being adapted for angular movement relative to said shell in a plane substantially at right angles to that of rotation of said supporting shell, receptacle contacts mounted on said supporting member and including a threaded 55 shell and a center contact, means electrically interconnecting the threaded shells of said plug and receptacle contacts, means electrically interconnecting the center contacts of said plug and receptacle including a conducting arm and 60 spring, said spring maintaining said supporting member and shell in assembled relationship on said plug base, and means for locking said supporting member and shell in angular relationship.

8. An adapter comprising a plug base having a recess therein at one end and being provided with an extension at the other end, said extension being formed with a channel therein, a spherically shaped shell rotatably mounted in 75

- the recess of said plug base, a supporting member pivotally mounted on said shell, receptacle contacts mounted on said supporting member, a conducting arm pivotally mounted on said supporting member and being in electrical engagement at one end with one of said receptacle contacts, the other end of said arm being formed with a flange, a bushing seated on said flange, a spring connected to said bushing and resting in the channel of said extension, an adjustable bolt forming a center plug contact and engaging the said spring to tension it and hold said supporting member and shell in assembled relationship on said base, and screw shell means forming the other of said plug contacts and being electrically connected to the other of said receptacle contacts.
9. In combination, an electric plug having a recess therein, a spherically shaped shell rotatably mounted in said recess, a supporting member of substantially spherical configuration rotatably mounted within said shell for angular movement relative thereto, receptacle contacts mounted on said supporting member, and spring means cooperating with said electric plug and said supporting member and being biased to hold them together, and means for adjusting the biasing action of said spring.
10. In combination, a base provided with electric terminal members, a member rotatably mounted on said base, a supporting element seated upon said rotatable member and adapted for angular movement relative to said member, receptacle contacts mounted on said supporting element, spring means interconnecting said supporting element and said base for maintaining said rotatable member and said supporting element in position on said base, said spring means forming an electrical conducting path between one of said base terminals and one of said receptacle contacts, and electrical conducting means interconnecting the other of said plug and receptacle contacts.
11. In combination, a base having a recess therein provided with electric terminal means, a metallic spherically shaped hollow shell rotatably mounted on said base, a supporting member of insulating material having a substantially spherical configuration, said supporting member being mounted within the hollowed portion of said shell for angular movement relative thereto, receptacle contacts mounted on said supporting member, and means electrically connecting said receptacle contacts with said electric terminal means.
12. An adapter comprising an electric plug provided with a base having a recess therein, contact members mounted on said base, a shell rotatably mounted within said recess, a supporting member seated within said shell and being mounted for angular movement relative to said shell and base, receptacle contact means mounted on said supporting member and including a screw threaded shell and a central contact member, a conducting arm pivotally mounted within said supporting member and electrically connected to said center contact member, spring means connected at one end to said arm and at the other end to one of said plugs to form a conducting path between said plug contact and said central contact, said spring means normally biasing said conducting arm to hold the supporting member and shell positioned on said base, and means electrically interconnecting said threaded shell and the other of said plug contacts.
13. An adapter comprising a plug base having a recess at one end and being provided with an extension at the other end, said extension being formed with a channel merging with said recess, a screw threaded shell mounted on the end of said extension and forming one plug contact, an adjustable member insulated from said shell and disposed within said channel to form another plug contact, a shell rotatably mounted in said recess, a supporting member seated within said shell and being angularly movable in a plane at right angles to that of the plane of rotation of said shell, receptacle contacts mounted on said supporting member and comprising a screw shell and a centrally disposed contact member, a conducting arm pivotally mounted within said supporting member and electrically connected to said center receptacle contact, spring means disposed between said conducting arm and said adjustable member, said spring means providing a conducting path from said adjustable member to said center contact and being adjustable on said member for holding the supporting member and shell in position on said plug base.
14. In combination, an electric plug, a spherically shaped shell rotatably mounted on said plug, a supporting member of substantially spherical configuration rotatably mounted within said shell for angular movement relative thereto, receptacle contacts mounted on said supporting member, and spring means cooperating with said electric plug and said supporting member and being placed under tension to hold said plug and member together for frictional movement relative to each other.
